UNITED STATES PATENT OFFICE

98,116

DESIGN FOR A MASS CARD HOLDER

William F. Liska, Chicago, Ill., assignor to Holland Brass Works, Incorporated, Chicago, Ill., a corporation of Illinois

Application April 4, 1935, Serial No. 56,198

Term of patent 7 years

To all whom it may concern:

Be it known that I, William F. Liska, a citizen of the United States, residing at Chicago, in the county of Cook and State of Illinois, have invented a new, original, and ornamental Design for a Mass Card Holder, of which the following is a specification, reference being had to the accompanying drawing, forming a part thereof.

Referring to the drawing, Fig. 1 is a front elevational view slightly in perspective of a mass card holder, showing my new design.

Fig. 2 is a side elevational view of the same.

I claim:

The ornamental design for a mass card holder, as shown.

WILLIAM F. LISKA.
